PUMP

Filed May 25, 1925

FIG. 1

FIG. 2

Patented Feb. 5, 1929.

1,701,309

UNITED STATES PATENT OFFICE.

LEO E. BUSH, OF INDIANAPOLIS, INDIANA.

PUMP.

Application filed May 25, 1925. Serial No. 32,681.

This invention relates to a dispensing device and particularly one for hydrocarbon or similar liquids, particularly gasoline.

The chief object of the invention is to provide what is commonly called a visible pump with a control mechanism for measuring the amount dispensed without the employment of a siphon heretofore employed.

The chief feature of the invention consists in the arrangement of the measuring mechanism in the form of at least three concentrically or coaxially positioned open ended tubes, arranged for telescopic movement and provided with valve means for closing the open end of the adjacent outer tube.

The full nature of the invention will be understood from the accompanying drawings and the following description and claims.

20 In the drawings Fig. 1 is a perspective view of a visible pump, parts being removed to illustrate other parts in detail. Fig. 2 is a vertical sectional view of the pump and measuring mechanism. Fig. 3 is a similar 25 view of a modified form of the invention.

In the drawings 10 indicates a suitable base, 11 a standard, tubular in form, terminating in a supporting head 12, which is provided with a transparent tubular chamber forming member 13 suitably protected by wire mesh or similar means 14. The chamber 13 is closed or covered by any suitable means such as the cover and advertising device 15. An over-flow pipe 16 determines 30 the initial or zero level of the liquid within the tank or chamber 13. Herein said chamber 13 is provided with a tubular discharge centrally positioned and indicated in Fig. 2 by the numeral 17. This tubular discharge 35 is provided with an outlet 18 connected to the usual hose 19 having a control valve 20. Any suitable means may be provided for supplying the liquid to be dispensed to the container or chamber 13, the surplus being 40 wasted or returned to the source of supply by means of the over-flow pipe 16.

The upper end of tube 17 is shown provided with a plurality of outlet forming notches 21. A valve 22 is rigid with a tube 50 23. When the valve 22 is raised above the level of the openings 21 by the telescopic or axial movement of tube 23 within tube 17, all of the liquid in the tank 13 above the level of the outlets 21 will be discharged 55 through tube 17 and discharge line 18. When the valve 22 is drawn downwardly into tube

17, no fluid can pass into tube 17 through ports 21.

Supported by tube 23 and extending coaxial therewith and above the same is a 60 tube 24, which tube 24 at its upper end is provided with the openings 25 similar to the openings 21. Therefore, when valve 22 is lowered in tube 17 by lowering the tube 23, the tube 24 is likewise lowered and the ports 25, if not otherwise controlled, will permit all of the liquid thereabove to discharge through tube 24 into tube 17 by means of the several ports 26 at the connection between the tubes 24 and 23.

Another tube 27 has an open upper end 28 and its lower end communicates with the tube 24 through the ports 29. A valve 30 is carried by tube 27 and is slideable therewith, said tube 27 and valve 30 being slideable by 75 a rod 31 which is co-axially arranged and extends through tubes 24, 23 and 17 and projects beyond them all. When the tube 27 is elevated so that valve 30 uncovers ports 25 all of the liquid thereabove will discharge 80 through outlet 18. When such is not the case the valve 30 is positioned below ports 25. All of the liquid then must be discharged through tube 27 by passing through the open mouth 28 provided valve 22 is positioned as 85 shown in Fig. 2. The device is so arranged that when valve 22 is opened the liquid contained within the tank between the top of the over-flow pipe 16 and the bottom port 21, is exactly ten gallons. The device is also 90 arranged so that when tube 24 is in predetermined position the amount of liquid contained within the tank between the level defined by the open upper end of the over-flow pipe 16 and the lower edge of the openings 25 is exactly six gallons.

The various possible combinations are as follows: When it is desired to have six or ten gallons respectively, the valves 30 and 22 respectively are elevated to open ports 25 and 21 respectively. When it is desired to have from one to five gallons, the two before mentioned valves are maintained in their closed relationship within their respective tubes and the tube 27 is lowered to any one 105 of its several positions for securing 1, 2, 3 or more gallons discharge through tube 27 to outlet 18. Fig. 2 shows the arrangement for securing one gallon. When from six to ten gallons is required, the mechanism is so 110 arranged that valve 30 is opened which will permit the discharge of six gallons. Likewise,

tube 24 is lowered, thereby lowering the discharge level of ports 25 and such lowering may be for one, two, three or more gallons, thereby giving a total discharge of seven, or 5 eight or more gallons, respectively.

The mechanism for readily determining the discharge amount is shown toward the bottom of Fig. 2, and comprises a plurality of rods carrying stops and cooperating handles. 10 Herein rod 40 is positioned in brackets 41 suitably secured to the tubular stand, or standard 11. Said rod 40 carries a plurality of stops 42, which are adjustably but rigidly mounted thereon, and at such distances that they correspond to the volumetric level difference for 15 the particular volumetric differences desired. If a suitable connection is effected whereby the positioning of the top of tube 24 is determined by one of the stops 42, the several positions of said tube 24 may be accordingly determined. A stop 43 is adjustably but rigidly mounted upon the lower end of tube 23 and said handle 44 is adapted to engage any one 20 of the several stops 42. If the uppermost stop is engaged then opening of the valve will discharge ten gallons. Engagement of the stop 43 upon second stop 42 will discharge six 25 gallons, each succeeding stop indicating the discharge of an additional gallon. Therefore, it is only necessary to provide thru supplementary or level determining stops, to wit, to secure from seven to nine gallon variations, six and ten gallon discharges being obtainable by opening the respective ports by shifting 30 tubes 27 and 24 respectively upwardly through opening the proper valve.

The rod 31 is slidably supported within tube 23 and has its lower free end slidably supported in a bracket 45. It carries an adjustable stop 46, having a handle portion 47, said stop 46 being rigidly secured to rod 31. When the handle 47 is positioned upon any one of the stops 42, carried by the rod 41, which is rigid with tube 23, valve 30 and tube 45 27 have relative movement with respect to tube 24. Thus, if the stop 46 engages the uppermost stop 42 the ports 25 are opened because the valve 30 is elevated thus securing a six gallon discharge, depending upon the position of said stop. Positioning of stop 46 by handle 47 engaging the next lowest stop 42 will secure the discharge of but one gallon, and positioning of said stop 46 upon successive stops 42 will secure successive discharges of additional gallons.

In Fig. 3 a modified form of the invention is illustrated and in this form, the capacity is but half of that previously described. In this form of the invention the standard 111 60 through base 112 supports the chamber 113

within which is positioned the tubular discharge 117. Telescopically associated therewith is the tubular construction 124, the upper end of which is open as at 128 and the other end of which supports a valve 122 for closing ports 121. A rod 131 is provided within tube 117 for reciprocating tube 124 and valve 123.

In Figs. 2 and 3 it will be noted that any desirable number of graduated discharges can be obtained, all of which are discharged from the same outlet 18. The invention, therefore, includes basically three or more telescopically arranged tubes each having an open upper end, the upper end of the outermost tube being closed by a valve carried by the inner tube. Likewise, the telescopic movement of the inner tube with respect to the outer tube may be graduated as desired for any suitable number of divisions of all of the volume included between the open ends of both tubes.

A further feature of the invention is herein illustrated particularly in the mid-portion of Fig. 2, and the same comprises a seal interposed between the two telescopically movable members, to wit, tubes 23 and 17. Said seal 50 includes a chamber 51 which is adapted to contain a fluid 52, such as castor oil or glycerine for a packing medium, said material being of such a mixture that it is not readily cut by the liquid dispensed through outlet 18. Similarly, there is also provided another seal 53 of similar character between the tube 23 and rod 17. No other seals are required.

The invention claimed is:

1. A measuring pump comprising a liquid receiving chamber, an over-flow pipe terminating near the top therein for initial level determination, a valve discharge for dispensing purposes, and a discharge level determining construction comprising three telescopic tubes, a plurality of said tubes being longitudinally movable, said tubes when in extended relation being arranged in superposed relation and each having an open mouth adjacent the upper end, and valve means on the lower ends of the superposed tubes for controlling the open mouth of the next lowest tube, said discharge communicating with the lowermost tube and each tube communicating with the other tubes.

2. A device as defined by claim 1, characterized by the addition of coaxially arranged extensions on the superposed tubes; and interlocking controls for selective positioning of said tubes.

In witness whereof, I have hereunto affixed my signature.

LEO E. RUSH.
